REINFORCEMENT FOR A TOOTH FILLING

Benjamin F. Tofflemire, Lafayette, Calif.

Application January 12, 1948, Serial No. 1,721

6 Claims. (Cl. 32—15)

1

The present invention relates to improvements in a reinforcement for a tooth filling. It consists of the combinations, constructions and arrangement of parts, as hereinafter described and claimed.

For restoring decayed and broken down teeth, unquestionably, amalgam is used more extensively than all other dental filling materials combined. When used carefully and conscientiously by operators of average skill and ability, it more nearly meets the requirements of the majority of patients than any other filling material that has been used in modern dentistry. Amalgam is used successfully by practically every dentist in general practice.

Some of the most serious objections to the use of amalgam in the past have been its lack of marginal edge-strength; its limited ability to resist "flow" when subjected to heavy masticatory stresses; its dimensional instability, particularly when the amalgam restoration is exposed to appreciable variations and elevations of mouth temperatures while eating, thereby accentuating the spheroidal tendency of the eutectic mixture, or low fusing alloy; and, finally, its inability to maintain permanently well-rounded contacts.

In order to overcome all of these inherent weaknesses at one fell swoop, I have devised a reinforcement for the amalgam fillings. For this purpose, I provide specially formed, instantly adaptable, silver inserts. These inserts have hardened contact points capable of withstanding permanent rugged service without either loss of the original summits of convexity of the contact points, or loss of the original normal interproximal embrasures and injury to the interseptal gingival tissues—all too often noticed in using amalgam which has not been stabilized by block silver reinforcing.

As an additional refinement in the use of reinforced amalgam work, I provide specially-formed matrix bands. These bands may be applied readily to a tooth by the dental matrix retainer disclosed in my copending application, Serial No. 721,995, filed in the United States Patent Office on January 14, 1947, now Patent No. 2,502,903, so that any variations in the axial contour, which may be necessary, can be obtained. The matrix bands are arranged to provide a seat for the insert.

It is further proposed to provide a self-separating matrix band, which will leave the contact point against an adjoining tooth, or contact points against teeth disposed on opposite sides of the tooth being filled, inviolate, uninjured, and capable of being cleaned and tested before dismissal of the patient—an achievement heretofore found impossible.

My matrix band adapts itself to the irregular conformation of the tooth upon which it is placed, and is notched at the point, or points,

where the band contacts an adjoining tooth or teeth. In one form, the matrix band is nickel plated in sections so as to withstand chemical action by the amalgam. Unplated sections are provided on the matrix band in the region of the notch or notches. These unplated sections are disintegrated by the amalgam, thus allowing the remaining portions of the band to be removed easily.

10 In a modified form, my matrix band is entirely nickel plated. The notch, or notches, which receive the end, or ends, of the inserts during the packing and condensing of the amalgam, facilitate breaking the band into sections prior to removal from the tooth.

Other objects and advantages will appear as the specification continues, and the novel features will be set forth in the claims hereunto appended.

15 For a better understanding of my invention, reference should be had to the accompanying drawings, forming part of this application, in which:

20 Figure 1 is an isometric view of a lower right first molar having a mesial-occlusal-distal cavity prepared therein, and further shows a matrix band clamped around the axial contour of the tooth by one of my dental matrix retainers;

25 Figure 2 is a longitudinal sectional view taken through the same molar from the mesial to the distal surfaces, and disclosing the cavity partially packed with amalgam and the insert anchored to the amalgam;

30 Figure 3 is a top plan view of the completely filled tooth as seen from the occlusal plane;

35 Figure 4 is a longitudinal sectional view taken along the line IV—IV of Figure 3;

40 Figure 5 is an elevation of a post provided on the reinforcing insert at either the distal or mesial end of the insert.

Figure 6 is a face view of one form of my matrix band;

45 Figure 7 is a face view of a modified form of matrix band;

Figure 8 is a view similar to Figure 4, but showing the cavity prepared in the distal-occlusal surfaces only;

50 Figure 9 is a top plan view of Figure 8, looking from the occlusal plane; and

Figure 10 is a view similar to Figure 9, but adding a lingual-occlusal reinforcing insert.

55 While I have shown only the preferred forms of my invention, it should be understood that various changes, or modifications, may be made within the scope of the annexed claims without departing from the spirit thereof.

Referring to the drawings in detail, Figures 1 to 4, inclusive, illustrate a lower right first molar, which is indicated generally at A. This tooth is situated between the second bicuspid B and the second molar C.

60 In order that the terms hereinafter used may

be fully understood, various parts of the lower right first molar A are designated by reference numerals as follows: 1—buccal surface (toward cheek); 2—lingual surface (tongue side); 3—mesial surface (toward mesial plane of the body); 4—distal surface (remote or away from the mesial plane); 5—occlusal surface; and 6—gingival (gum) border. This molar has a mesial-occlusal-distal cavity D therein, the various parts of which are designated by reference numerals as follows: 7—floor of cavity; 8—axial walls; 9—gingival floors; and 10—cavo surfaces. The axial contour of the tooth is indicated at 11, and this contour is conical-shaped and tapers inwardly toward the roots or fangs 12.

Figure 1 shows a matrix band E, which encircles the molar A and is drawn tightly against the axial contour 11 of the tooth by a dental matrix retainer F. This retainer is disclosed and described in detail in my copending application, Serial No. 721,995, filed January 14, 1947, and referred to in the objects of this application.

Briefly described, the retainer F includes a bar-like frame 14 on which a matrix-clamping block 15 is slidably mounted. The frame 14 has a head 16 thereon, which defines four parallel and spaced-apart fingers 17, 18, 19 and 20. The ends 21 of the matrix band E are accommodated in a diagonally-extending slot 22 formed in the block 15, and are clamped thereto by a spindle 23 that is threaded into the block. The spindle is rotated by an operating knob 24. A rotatable internally-threaded sleeve 25 is held against endwise movement relative to the frame 14. When this sleeve is turned, the spindle 23 and the clamping block 15 are advanced or retracted relative to the head 16.

In Figure 1, I show the matrix band as passing between the fingers 17—18 and then guided through the slot provided between the fingers 18—20. When the block 15 is retracted, the matrix band E will be drawn up tightly against the axial contour 11 of the tooth A.

The matrix band E illustrated in Figure 6 is made of a material, such as brass, that will be acted upon chemically by amalgam and cause the material to disintegrate. The band has nickel plated sections 26, which will resist chemical reaction of the amalgam. The intermediate sections 27 of the band are unplated and are exposed to the action of the amalgam during packing of the latter in the tooth. Consequently, by the time the restoration of the tooth is completed, the sections 27 will become disintegrated or at least made so thin that the sections 26 may be removed readily from around the tooth.

Notches 28 are fashioned in the upper edge of the matrix band. These notches are spaced apart sufficiently so that one notch can be placed on the mesial surface or aspect 3 of the tooth A, and the other notch located on the distal surface or aspect 4 of the same tooth.

It will be noted from Figure 6 that the matrix band E is curved lengthwise when the band is flat. The intermediate portion of the band will become conical-shaped when drawn tightly around a tooth (see Figure 2). The band extends downwardly at least to the gingival floor 9.

Referring now to Figures 2 to 5, inclusive, I show an insert G, which is made for reinforcing a mesial-occlusal-distal filling. This insert includes a bar-like member 29 of zig-zag configuration, as shown in Figure 3, and designed for overlying the main cavity floor 7 in spaced relation therewith. The ends of this member have posts 30 depending therefrom. Each post tapers to a point 31 dis-

posed at the bottom thereof. Figures 3 and 4 disclose the tops 32 of the posts as being wider than the member 29 so as to project laterally beyond the member toward the cavo surfaces 10. The bar-like member 29 and the posts 30 preferably are made of silver so that amalgam will bond chemically thereto.

Lugs 33 of hardened material, such as gold, project from opposing faces of the posts 30 in directions to contact with the teeth B and C, which are disposed on opposite sides of the molar A in which an amalgam filling will be packed. These lugs project into the notches 28 of the matrix band E and are supported by the latter (see Figure 2).

An important structural feature of the insert G is the zig-zag configuration of the bar-like member 29. The over-all length of the insert will be made so as to correspond approximately with the distance between the teeth B and C. However, in the event that the lugs 33 do not contact with the teeth B and C, the length of the member 29 can be extended by merely gripping opposite corners 34 of the member with a pair of pliers, or the like, and squeezing the jaws of the pliers toward one another to elongate the member 29. In case the member 29 is over-extended, the tips of the lugs 33 can be ground down. The primary point to bear in mind is that the lugs 33 must contact with the teeth that are located on opposite sides of the tooth in which the insert is applied.

Prior to introducing the insert E into the cavity D, a body of amalgam H, or partial filling, is applied over the cavity floor 7, the axial walls 8 and gingival floors 9. The body H of amalgam extends to the inner walls of the matrix band. Thereafter, the insert E is placed in the cavity D and the posts 30 are pushed downwardly into the body of amalgam H. The bar-like member 29 should be substantially parallel with the cavity floor 7 and the posts substantially parallel relative to the axial walls 8. The lugs 33 will come to rest in the notches 28 and contact the teeth B and C. Figure 2 shows the restoration up to this point, and the matrix band E is still in place around the axial contour of the tooth A. The body of amalgam H will unite chemically with the insert.

As the next step, an upper layer of amalgam J is packed and condensed over the insert, as shown in Figures 3 and 4. By this time, the unplated sections 27 of the matrix band have disintegrated, or at least weakened, by the amalgam acting on the brass. The dental matrix retainer 50 F is removed and the plated sections 26 of the band E are removed. The member 29 could be arranged in registry with the occlusal surface of the amalgam filling, if desired.

The posts 30 project laterally toward the cavo surfaces 10 so as to reinforce the amalgam filling disposed between the surfaces 10 at the mesial and distal portions of the tooth. Normally, this is a very vulnerable part of the filling.

Figure 7 illustrates a modified form of a matrix band, which is designated at E'. In this modification, the entire surface of the band is nickel plated, as suggested by the color shading. This band has the same shape as the one shown in Figure 6, and is provided with notches 28' in its upper edge. After the amalgam filling has been packed and condensed, the band E' is broken at points below the notches 28', as indicated by the break lines 35 in Figure 7. This will allow the band E' to be withdrawn in three sections.

Turning now to Figures 8 and 9, it will be noted

that a distal-occlusal cavity D' has been prepared in a tooth A'. The insert G' is really one-half of the insert G previously described. Accordingly, like reference numerals will be applied to corresponding parts. In this form, the end 29a abuts the central axial wall 36 of the cavity, while the lug 33 has contact with the tooth C'. Figures 8 and 9 disclose the tooth A' as contacting with an adjacent tooth B'. The method of filling the cavity D' in Figures 8 and 9 is identical with that described in connection with Figures 1 to 5, inclusive. Also, the insert is made of silver so that it will unite chemically with the amalgam bodies H and J.

Figure 10 is identical with Figure 9, excepting that a lingual-occlusal cavity D'' has been added in the tooth A''. A silver insert G'' has been placed in this cavity to reinforce the amalgam filling K therein. The teeth on opposite sides of the tooth A'' are designated at B'' and C''. The tooth A' has a distal-occlusal cavity D' therein in which an insert G' is disposed to reinforce the amalgam filling J''. The method of restoring the tooth A'' is the same as that set forth in connection with Figures 8 and 9, except for the addition of the insert G''.

It is obvious that the cavities in Figures 8 to 10, inclusive, could extend in a mesial-occlusal direction, if the decay in the tooth being filled required such a cavity to be prepared.

The inserts that I have disclosed may be applied readily and are provided with hardened lugs, or contact points, that will withstand rugged service without loss of the original summits of convexity of the contact points, or loss of the original normal interproximal embrasures. They will prevent injury to the interseptal gingival tissues. The amalgam fillings will withstand heavy masticatory stresses, maintain their dimensions and resist spheroidal tendency. Also, they will maintain well-rounded contacts. No galvanic action will take place, and the inserts become permanently bonded to the amalgam fillings. The hardened lugs on the inserts prevent food from packing between adjacent teeth. The strength of the fillings will be increased tremendously over ordinary amalgam fillings.

Although I have referred to using my inserts for reinforcing amalgam fillings, I wish to make it clear that other types of fillings, such as porcelain, could be reinforced with the inserts. When amalgam is employed, it is desirable to form the inserts from silver, since the amalgam and silver inserts will bond together chemically. The lug or lugs 33 may be made from any suitable hardened metal, for instance, low carat gold solder or other case-hardened metal, and I do not wish to be limited to gold alone.

I claim:

1. As an article of manufacture: a bar-like member designed to be embedded in a filling of a tooth to reinforce the filling; a post depending from one end of the member for embedment in the filling; and a restricted lug projecting from the post on the side of the latter opposite to the member; the lug being dimensioned to extend beyond the axial contour of the tooth to provide a restricted interproximal contact point bearable against an adjacent tooth.

2. As an article of manufacture: a bar-like member designed to be embedded in a filling of a

tooth to reinforce the filling; a post depending from one end of the member for embedment in the filling; and a restricted lug projecting from the post on the side of the latter opposite to the member; the lug being dimensioned to extend beyond the axial contour of the tooth to provide a restricted interproximal contact point bearable against an adjacent tooth; the bar-like member being zig-zag in configuration, and defining convolutions winding back and forth on first one side of the member and then on the other; the member being sufficiently pliable for flattening out of its convolutions to extend the over-all length of the member.

3. As an article of manufacture: a bar-like member designed to be embedded in a filling of a tooth to reinforce the filling; a pair of posts depending from opposite ends of the member for embedment in the filling; and preformed lugs projecting from the posts on the sides thereof opposite to the member; the lugs being dimensioned to extend beyond the axial contour of the tooth to provide restricted interproximal contact points bearable against teeth disposed on the mesial and distal aspects of the tooth in which the member is disposed.

4. As an article of manufacture: a bar-like member designed to be embedded in a filling of a tooth to reinforce the filling; a pair of posts depending from opposite ends of the member for embedment in the filling; and preformed lugs projecting from the posts on the sides thereof opposite to the member; the lugs being dimensioned to extend beyond the axial contour of the tooth to provide restricted interproximal contact points bearable against teeth disposed on the mesial and distal aspects of the tooth in which the member is disposed; the bar-like member being zig-zag in configuration, and defining convolutions winding back and forth on first one side of the member and then the other; the member being sufficiently pliable for flattening out of its convolutions to spread the posts farther apart.

5. In combination: a looped matrix band having a notch fashioned in an upper edge thereof; and a bar-like member disposed within the loop of the matrix band; the member having a lug projecting into the notch of the matrix band and supporting one end of the member.

6. In combination: a looped matrix band having notches fashioned in an upper edge of the band at diametrically-opposed sections of the looped band; and a bar-like member disposed within the loop of the matrix band; the member having lugs projecting into the notches of the matrix band and supporting both ends of the member.

BENJAMIN F. TOFFLEMIRE.
